[57] ABSTRACT

A static flip-flop circuit constructed of field-effect transistors, wherein a static section comprises a field-effect transistor which allows an information to be held during its conductive state and a new information to be written during its non-conductive state and which dispenses with a transfer gate otherwise included in a feedback path of such static section, so that the likelihood of an erroneous operation attributable to charge sharing is eliminated.

FLIP-FLOP CIRCUIT

BACKGROUND OF THE INVENTION

1. Field of the Invention

The present invention relates to a flip-flop circuit, and more particularly to a static flip-flop circuit employing field-effect transistors.

2. Description of the Prior Art

Flip-flop circuits constituted of insulated gate field-effect transistors are broadly classified into the dynamic flip-flop circuit and the static flip-flop circuit. Although the former is simple in construction, the latter is sometimes more preferable in consideration of its retention of information.

FIG. 1 shows a prior art static flip-flop circuit constructed of field-effect transistors.

The flip-flop circuit in the figure comprises the first inverter circuit composed of transistors T_{11} and T_{12} , the second inverter circuit composed of transistors T_{14} and T_{15} , the third inverter circuit composed of transistors T_{16} and T_{17} , and transistors T_{13} , T_{18} and T_{19} for transfer gates. The second inverter circuit and the third inverter circuit are connected in cascade. An output terminal of the third inverter circuit is connected for feedback with an input terminal of the second inverter circuit through the transistor for the transfer gate T_{18} . Information is retained by the feedback loop. Contents of the information retained within the above feedback loop depend on the state of that output of the first inverter circuit at the time of conduction of the transistor for the transfer gate T_{13} . A clock signal ϕ_2 is applied to the gate electrodes of the transistors T_{18} and T_{19} , while a clock control signal ϕ_1 differing in phase from the signal ϕ_2 is applied to the gate electrode of the transistor T_{13} .

Here, the flip-flop circuit drives the load transistors T_{12} , T_{15} and T_{17} with a DC supply voltage V_{DD} . In case where, in order to render the power consumption low, the transistors are driven by clock pulses, the problem of charge sharing arises as will be stated hereunder.

By way of example, it is assumed that the transistor T_{12} is driven by the clock control signal ϕ_1 , while the transistors T_{15} and T_{17} are driven by the clock signal ϕ_2 . An electric potential impressed on the gate electrode of the transistor T_{14} before the transistor T_{13} is turned on by the clock control signal ϕ_1 to thereby write a new information into the feedback loop, is supposed to be ground potential. Accordingly, no charge is held stored in the gate capacity C_1 of the transistor T_{14} and a capacity C_2 formed by the wiring capacity between the transistors T_{16} and T_{18} and so forth. Subsequently, the new information is written, the gate capacity C_1 of the transistor T_{14} is charged, and the potential of the gate electrode reaches V . Then, when the transistor T_{18} is turned on by the clock signal ϕ_2 , the gate potential of the transistor T_{14} lowers to $V \cdot C_1/(C_1 + C_2)$, and hence, it is feared that the transistor T_{14} is prevented from operating satisfactorily. The phenomenon becomes the cause of an erroneous operation, and imposes restrictions on the value of the wiring capacity C_2 .

SUMMARY OF THE INVENTION

An object of the present invention is to provide a static flip-flop circuit which is constituted of field-effect transistors and for which both the DC drive and the clock drive are possible.

According to the present invention, there is provided a flip-flop circuit comprising a static section which is

composed of the first field-effect transistor connected to the first load resistance means, the second field-effect transistor connected to the second load resistance means, and the third field-effect transistor connected in series with the second field-effect transistor, and in which an output electrode of the first field-effect transistor is connected to an input electrode of either one of the second and third field-effect transistors, while the second pulse signal is applied to an input electrode of the other, and an output electrode of the second field-effect transistor is connected for feedback to an input electrode of the first field-effect transistor. In addition to the static section, the flip-flop circuit comprises the fourth field-effect transistor for a transfer gate, which is connected between an input signal source and the input electrode of the first field-effect transistor of the static section and which has the first pulse signal applied to its input electrode. The above-mentioned first and second pulse signals differ in phase from each other.

With the flip-flop circuit of such construction, information can be always stored in the static section. Writing of a new information is performed in such a way that the fourth field-effect transistor for the transfer gate is turned on by the first pulse signal, to apply an input signal to the input electrode of the first field-effect transistor. It will become apparent from the following description of the preferred embodiments that both the DC drive and the clock drive are possible.

BRIEF DESCRIPTION OF THE DRAWINGS

FIG. 1 is a circuit diagram of the prior art static flip-flop circuit which has been explained previously;

FIG. 2 is a circuit diagram of a static flip-flop circuit with DC drive according to the present invention;

FIG. 3 is a time chart for the flip-flop circuit in FIG. 2 and the flip-flop circuit in FIG. 4; and

FIG. 4 shows the static flip-flop circuit of the clock drive according to the present invention.

PREFERRED EMBODIMENTS OF THE INVENTION

Referring now to the accompanying drawings, the flip-flop circuit according to the present invention will be described.

FIG. 2 is a schematic circuit diagram of a static flip-flop circuit constructed of field-effect transistors, and illustrates a case where load transistors are driven by DC power sources.

In the figure, transistors T_6 , T_8 and T_9 function as load resistances. A DC source voltage $-V_{CC}$ is applied to each gate electrode, while a DC source voltage $-V_{DD}$ is applied to each drain electrode.

The drain electrodes of transistors T_1 and T_2 are connected to the source electrodes of the load transistors T_6 and T_8 , respectively. The source electrode of the transistor T_1 is grounded, but that of the transistor T_2 has the drain electrode of a transistor T_3 connected thereto. The source electrode of the transistor T_3 is grounded. An output electrode of the transistor T_1 , namely, the drain electrode thereof is connected to an input electrode of the transistor T_2 , namely, the gate electrode thereof. The output electrode of the transistor T_2 is feedback-connected to the input electrode of the transistor T_1 .

Transistors T_9 and T_{10} constitute an inverter circuit, whose output signal is applied through a transistor for

a transfer gate T_4 to the input electrode of the transistor T_1 .

A transistor T_5 is used as a transistor for a transfer gate which, when rendered conductive, transmits an output signal of an inverter circuit constituted of the transistors T_1 and T_6 to an output terminal OUT.

To the input electrode or gate electrode of the transistor T_4 , a clock control signal ϕ_x is applied. To the gate electrode of the transistor T_3 , the inverted signal ϕ_x of the above signal is applied. To the gate electrode of the transistor T_5 , a clock signal ϕ_2 is applied.

The operation of the flip-flop circuit of the embodiment will now be explained with reference to a time chart in FIGS. 3a to 3g.

FIG. 3a represents the clock signal ϕ_2 ; FIG. 3b represents an input signal applied to an input terminal IN; FIGS. 3c and 3d represent the clock control signals ϕ_x and $\bar{\phi}_x$, respectively; FIGS. 3e and 3f represent electric potentials at points *a* and *b* in FIG. 2, respectively; and FIG. 3g represents an electric potential at the output terminal OUT. In the time chart, the upper level of each signal indicates ground potential, and the lower level a predetermined negative potential. Although the respective transistors will be explained as being the P-channel field-effect transistors which are rendered conductive upon application of a predetermined negative potential to the gate electrodes, it is a matter of course that the present invention is not restricted thereto.

Briefly stated, the operation of the flip-flop circuit in FIG. 2 is as follows. While the transistor T_3 is kept conductive, an information is statically held by the feedback circuit including the transistors T_1 , T_2 and T_3 . Next, when a new information is written into the feedback circuit, that is when the clock control signal ϕ_x falls to the negative potential so as to render the transfer gate transistor T_4 conductive, the transistor T_3 on which the inverted signal of the above signal is impressed becomes non-conductive. An electric potential impressed on the gate electrode of the transistor T_1 is forced into the output potential of the transistor T_{10} independent of the previous state. In this way, the new information is written into the aforesaid feedback circuit. It is statically held in the feedback circuit until the transfer gate transistor T_4 is thereafter rendered conductive again to thus effect the next writing.

As understood from the time chart in FIG. 3, the potential V_a of the gate electrode of the transistor T_1 (the potential of the point *a*) becomes the potential of the inverted signal of the input signal V_{in} when the clock control signal ϕ_x falls into the negative potential, and holds the state until the clock control signal ϕ_x is subsequently brought into the negative potential again. The output potential of the transistor T_1 , namely, the potential V_b of the point *b* is merely the inverted one of the potential V_a of the point *a*. The output potential V_{out} is delayed with respect to the potential V_b of the point *b* by the clock signal ϕ_2 .

Referring now to FIG. 4, description will be made of a static flip-flop circuit in which load transistors are subjected to the clock drive.

In FIG. 4, the same parts as in FIG. 2 are designated by the same symbols.

In the embodiment in FIG. 4, the gate electrode of the load transistor T_9 has the clock control signal ϕ_x supplied thereto. The gate electrode of the load transistor T_6 has the clock control signal ϕ_x similarly supplied thereto. A load transistor T_7 is connected in parallel

with the load transistor T_6 . The gate electrodes of the load transistors T_7 and T_8 have the clock signal ϕ_2 supplied thereto.

The operations of the load transistors with the predetermined clock signals thus applied to their gate electrodes, are as follows.

When the clock control signal ϕ_x falls into the negative potential, the load transistor T_9 is rendered conductive, and the output potential of the transistor T_{10} is determined. The load transistor T_{10} is low in power consumption since it is rendered conductive only when a new information is written, that is, only when the clock control signal ϕ_x becomes negative.

The load transistor T_6 is similarly rendered conductive at the writing of the new information, to determine the potential of the point *b*. In the case where, at the writing of an information, the ground potential of the new information is transmitted through the transfer gate transistor T_4 to the point *a*, and yet, the point *b* is at the ground potential of an old information, the state of the flip-flop circuit is not definitely settled. The load transistor T_6 is used in order to avoid the inconvenience. More specifically, the transistor T_1 is non-conductive and the load transistor T_6 is conductive in this case, so that the potential of the point *b* is rewritten from the ground potential of the old information to the negative potential of the new information.

The load transistor T_7 is rendered conductive when the clock signal ϕ_2 falls to negative potential. It determines the potential of the point *b*. In the case where the period of the clock control signal ϕ_x is long, that is, where the interval of the writing of an information is large, charges accumulated in the gate capacity of the transistor T_2 are gradually lost, which constitutes a cause of an erroneous operation. In order to avoid the inconvenience, the load transistor T_7 charges the gate capacity of the transistor T_2 at the period of the clock signal ϕ_2 .

The transistor T_8 is similarly rendered conductive when the clock signal ϕ_2 is brought to negative potential. The output potential of the transistor T_2 is thereby determined.

In accordance with the flip-flop circuit of such construction, the transfer gate transistor T_{18} is not incorporated into the feedback path as is done in FIG. 1, that is, the capacity is not divided into the components C_1 and C_2 by the transfer gate transistor T_{18} as is done in FIG. 1, so that any erroneous operation due to the aforesaid charge sharing does not take place. Therefore, not only the DC drive, but also the clock drive is also possible.

While, in the above, the present invention has been described in conjunction with the embodiments, it is not restricted to them but it allows a variety of modifications.

For example, the clock control signal ϕ_x may be applied to the gate electrode of the transistor T_2 , while the output electrode of the transistor T_1 may be connected to the gate electrode of the transistor T_3 . A pulse signal differing in phase from the clock control signal ϕ_x , e.g., the clock signal ϕ_2 may be fed to the gate electrode of the transistor T_2 or T_3 . The clock control signal may be a clock signal obtained by delaying the phase of the clock signal ϕ_2 , or may be a signal obtained by taking a logic result between the clock signal and another pulse signal. The output signal may be derived, not only from the point *b*, but also from the output electrode of

the transistor T_2 through the transfer gate transistor T_5 . Various sorts of logical gate circuits, such as inverter circuits, may be connected between the foregoing feedback circuit or static section and the transfer gate transistors T_4 and T_5 .

What is claimed is:

1. A flip-flop circuit comprising a first field-effect transistor connected to first load resistance means, a second field-effect transistor connected to second load resistance means, a third field-effect transistor connected in series with said second field-effect transistor, a transfer gate including a fourth field-effect transistor connected between an input signal source and an input electrode of said first field-effect transistor, means for applying a first pulse signal to an input electrode of said fourth field-effect transistor, an output electrode of said first field-effect transistor being connected to an input electrode of one of said second and third field-effect transistors, means for applying a second pulse signal different in phase from said first pulse signal to an input electrode of the other of said second and third field-effect transistors, and substantially zero impedance means for feedback-connecting an output electrode of said second field-effect transistor directly to said input electrode of said first field-effect transistor. 15

2. A flip-flop circuit according to claim 1, further including an additional transfer gate including a fifth field-effect transistor connected to said output electrode of one of said first and second field-effect transistors, means for applying a third pulse signal different in phase from said first pulse signal to an input electrode of said fifth field-effect transistor. 20

3. A flip-flop circuit comprising a first field-effect transistor connected to first load resistance means, a second field-effect transistor connected to second load resistance means, a third field-effect transistor connected in series with said second field-effect transistor, a transfer gate including a fourth field-effect transistor connected between an input signal source and an input electrode of said first field-effect transistor, means for applying a first pulse signal to an input electrode of said fourth field-effect transistor, an output electrode of said first field-effect transistor being connected to an input electrode of one of said second and third field-effect transistors, means for applying a second pulse signal different in phase from said first pulse signal to an input electrode of the other of said second and third field-effect transistors, an output electrode of said second field-effect transistor being connected for feedback to said input electrode of said first field-effect transistor, an additional transfer gate including a fifth field-effect transistor connected to said output electrode of one of said first and second field-effect transistors, means for applying a third pulse signal different in phase from said first pulse signal to an input electrode of said fifth field-effect transistor, said first load resistance means comprising sixth and seventh field-effect transistors which are connected in parallel with each other and whose input electrodes are respectively connected to receive said first and third pulse signals. 45

4. A flip-flop circuit according to claim 3 wherein said second load resistance means comprises an eighth field-effect transistor whose input electrode is connected to receive said third pulse signal.

5. A flip-flop circuit according to claim 4 wherein the 60

drain electrode of said first field-effect transistor is connected to the gate electrode of said second field-effect transistor.

6. A flip-flop circuit according to claim 5 wherein said fifth field-effect transistor is connected to the output electrode of said first field-effect transistor.

7. A flip-flop circuit according to claim 1 wherein said first and second load resistance means comprise respective fifth and sixth field-effect transistors.

8. A flip-flop circuit according to claim 1 wherein said input signal source includes an inverter circuit formed by fifth and sixth field-effect transistors connected in series.

9. A flip-flop circuit comprising:

a first load means;
a first insulated gate type field-effect transistor connected with said first load means;
a second load means;
series connected second and third insulated gate type field-effect transistors connected with said second load means;
a fourth insulated gate type field-effect transistor connected between an input signal source and a gate electrode of said first field-effect transistor;
substantially zero impedance means for connecting an output electrode of said first transistor with a gate electrode of one of said second and third transistors;

substantially zero impedance means for connecting an output electrode of said series connected second and third transistors with the gate electrode of said first transistor;

means for supplying a first pulse signal to a gate of said fourth transistor; and
means for supplying a second pulse signal to a gate of the other of said second and third transistors.

10. A flip-flop circuit comprising:
a first and a second voltage line; a first load means one electrode of which is connected to said first voltage line;
a first insulated gate type field-effect transistor connected between said second voltage line and the other electrode of said first load means;
a second load means one electrode of which is connected to said first voltage line;
series connected second and third insulated gate type field-effect transistors connected between said second voltage line and the other electrode of said second load means;
a fourth insulated gate type field-effect transistor connected between an input signal source and a gate electrode of said first field-effect transistor;
substantially zero impedance means for connecting an output electrode of said first transistor with a gate electrode of one of said second and third transistors;

substantially zero impedance means for connecting an output electrode of said series connected second and third transistors with the gate electrode of said first transistor;

means for supplying a first pulse signal to a gate of said fourth transistor; and
means for supplying a second pulse signal to a gate of the other of said second and third transistors.
